D8-310. OR D14,928 EX

No. 14,928,

Apr. 1- 1884-

UNITED STATES PATENT OFFICE.

FRANCIS KEIL, OF NEW YORK, N. Y.

DESIGN FOR ORNAMENTATION OF BUILDERS' HARDWARE.

SPECIFICATION forming part of Design No. 14,928, dated April 1, 1884.

Application filed November 7, 1883. Term of patent 7 years.

To all whom it may concern:

Be it known that I, FRANCIS KEIL, a citizen of the United States of America, residing in the city, county, and State of New York, have 5 invented and produced a new and original Design for Ornamental Panels on Builders' Hardware, of which the following is a specification, reference being had to the accompanying photograph, which is a part hereof.

10 The photograph shows a perspective view of the design as applied to an escutcheon and door-knob.

15 The leading feature of my design consists of ornamenting the recessed panel or ground-work with a series of circles having a raised center, from which curved sunken rays run toward the inner side of the circle, which is also sunken. Between these circles I arrange 20 raised bars, having their sides converging inwardly toward each other. At the ends of the bars is a raised circular portion, as at *z*. The outer edge of the escutcheon, as well as the hinges and other articles, is provided with 25 a raised border. The hinge has inside of the border just mentioned, down the side, another narrow raised bar. Between the bar and border are small raised diamonds. In the center of the diamonds I provide four small round 30 raised beads. A hollow triangle fills the space between the sides of the diamonds and the raised bar and border. At the upper and lower end of the hinge are two ornamentations consisting of two raised narrow bars. Between these bars a raised scroll is provided, 35 having its base attached to the inner bar and then curved upward and inwardly. The end, which is provided with a small round part, is turned upward and crosses the loop, giving it somewhat the appearance of an *L*. In the 40 loop a shamrock-leaf is provided. On the outside of the bars small ornamentations are provided, preferably those shown in the pho-

tograph. At the ends inside of the border I provide a row of pearls. The lips of the hinge are round, and of any suitable shape 45 and ornamentation. In the escutcheon, between the key-hole and the knob-hole, a raised ornamentation such as above is described. At the ends the escutcheon is provided with a half-disk, the outer edge of which is beaded. 50 A raised half-ring flush with the border proper is provided. Inside of this ring a scalloped raised ornament is provided. The main ornamentation of the door-knob is the configuration of the circles and bars, as heretofore 55 described. In the center of the knob is a raised ring. Inside of this ring I provide a series of beads; outside of the ring, any suitable ornamentation. When the sunken part is circled and barred, as hereinbefore described, then another raised ring is provided. Around the outside of this ring I provide another narrower raised ring. Between these last two mentioned rings a series of scallops are provided. The edge of the knob is beaded, 60 and thus a better grip is afforded. The leading feature of my design, however, is the circled and barred sunken panel, together with the raised relief ornamentations.

What I claim as new, and desire to secure 70 by Letters Patent, is—

The design for ornamentation of builders' hardware, consisting of a sunken panel, the groundwork of the panel having a series of circles provided with the raised center, from 75 which run the curved rays, with the bars and raised center between the circles, as described and shown.

In testimony whereof I affix my signature in presence of two witnesses.

FRANCIS KEIL.

Witnesses:

L. J. HIGHAM,
JOSEPH STRACKE.
